E. M. BEADLE

COMBINED HEMMER AND TUCKER

Filed Sept. 20, 1920

Patented Oct. 23, 1923.

1,471,719

UNITED STATES PATENT OFFICE.

ELLA M. BEADLE, OF LYONS, NEW YORK.

COMBINED HEMMER AND TUCKER.

Application filed September 20, 1920. Serial No. 411,639.

To all whom it may concern:

Be it known that I, ELLA M. BEADLE, a citizen of the United States, residing at Lyons, in the county of Wayne, State of New York, have invented certain new and useful Improvements in Combined Hemmers and Tuckers; and I do hereby declare the following to be a full, clear, and exact description of the same, reference being had 10 to the accompanying drawing, forming a part of the specification, and to the reference numerals marked thereon.

This invention relates to improvements in hemming and tucking attachments for sewing machines and has for its object to provide a device of simplified construction and easy adjustment which is adapted to function as either a hemmer or a tucker. To these and other ends the invention consists 20 in certain improvements and combinations of parts, all as will be hereinafter more fully described, the novel features being pointed out in the claims at the end of the specification.

25 In the drawings:

Figure 1 shows a top plan view of my attachment applied to a sewing machine and used as a hemmer.

Figure 2 is an end view of the device 30 shown in Figure 1.

Figure 3 is a plan view of my attachment in operation as a tucker.

Figure 4 is a top plan view of the left hand end of the plate 13 shown in Figures 35 1 and 3.

Figure 5 is a section on the line 5^a—5^a of Figure 1.

Figure 6 is a section on the line 6^a—6^a of Figure 3.

40 Figure 7 shows a modified form of supporting device.

Figure 8 is a section on the line 8^a—8^a of Figure 3.

Similar reference characters throughout 45 the several views indicate the same parts.

In the drawings the numeral 1 indicates the bed of the usual sewing machine provided with the customary presser foot 2 and shank 3 therefor with which the needle 50 4 cooperates in sewing the seam 5 in the goods 6. Sewing machines are usually provided with a set screw 7 on the bed to which may be attached the supporting device 8 for my combined hemming and tucking attachment. As shown the support 8 is provided at 55 each end with adjusting slots arranged sub-

stantially at right angles to one another and in which are placed the clamp screws 7 and 9 respectively. The clamping screw or device 9 adjustably positions two plates or members 10 and 13 comprising my combined hemmer and tucker. The slotted plate 10 is provided at its right end with a down-turned extension or edge in the form of a work guiding hook or gauge 11 which is shown as being perforated at 12 for insertion of the prongs of the other plate 13. If desired suitable graduations may be placed on the plate 13 in order to indicate the relative position of these two plates 10 and 13. At its left end plate 13 is also provided with a down-turned edge 14 adapted to serve as a gauge or guiding hook for the material in sewing, but of less depth than hook 11 as is indicated in Figure 2. 75 Provided on the gauge 14 but laterally disposed relative to the plate 13 is an up-turned lip 15 which is adapted to be employed to turn in the edge of the goods when the device is used as a hemmer. By 80 having the turning lip 15 disposed at the side of the plate 13 the turning lip will not turn or hem the goods nor prevent the hook 14 serving as a gauge when the attachment is used as a tucker.

Those standard makes of machines which are not supplied with the clamp screw 7 are provided with some similar clamping means on the presser foot, and in these machines it will be desirable to use some form of support as shown in Figure 7, which is provided 90 with a groove 16 for the reception of the clamp screw on the presser foot and with another groove 17 on its other end for the reception of the clamping means 9.

In operation as a hemmer Figure 1 shows the arrangement of parts from which their co-operation will be readily seen. The width of the hem depends upon the separation of the gauges 11 and 14. In order to 100 change the position of the seam 5 relative to either edge of the hem the device as a whole may be moved along the support by means of the adjusting clamp 9 or by means of moving the support 8 relative to the clamp screw 7. Figure 3 illustrates the arrangement of parts when the attachment is used for tucking. Figure 5 represents a section through the goods after sewing hem 18. In operation as a tucker the spacing of the gauges 11 and 14 relative to one another determines the separation of the 105 110

tucks 19 while the distance of the gauge 11 from the needle 4 determines the size of the tucks. From Figure 3 it will be seen that the single adjusting or clamping means 9 may be used to determine both the spacing of the tucks as well as the depth of each tuck, that is, by loosening the clamping means 9 the relative adjustment of the plates 10 and 13 may be varied as well as the position of these plates in respect to the needle.

Among the advantages of my combined hemming and tucking attachment may be mentioned the fact that because the turning lip 15 is laterally disposed to the plate 13 the lip is not in the way of the goods when the device functions as a tucker. Instead of having several adjustments to vary the size of the tucks as well as the spacing thereof, a single adjusting or clamping means 9 is afforded to take care of both adjustments, which means controls the adjustment of both the gauges 11 and 14. The easily adjustable support 8 affords a ready and simplified means of moving the combined hemming and tucking attachment along as well as transversely of the seam.

I claim as my invention:

1. A combined hemming and tucking attachment for sewing machines comprising a pair of overlapping plates, downward extensions on the overlapping portions of the plates forming work guides, one of said plates being slidably carried in a slot in the downward extension of the other plate with said extensions in adjustably opposed relation, a folding lip on one of said work guides disposed laterally of said plates, and

a device for adjustably clamping said overlapping plate portions together. 40

2. A combined hemming and tucking attachment for sewing machines comprising a pair of overlapping plates, downward extensions on the overlapping portions of the plates forming work guides, one of said plates being slidably carried in a slot in the downward extension of the other plate with said extensions in adjustably opposed relation, and means adjustably supporting each of said plates. 45

3. A combined hemming and tucking attachment for sewing machines comprising a pair of overlapping plates, downward extensions on the overlapping portions of the plates forming work guides, one of said plates being slidably carried in a slot in the downward extension of the other plate with said extensions in adjustably opposed relation, a supporting arm for attachment to the sewing machine, and a device 55 adjustably connected with said arm and with each of said plates for clamping the plates together and to said arm. 60

4. In a tucking attachment the combination with a slotted plate provided with a down-turned edge forming a gauge adjacent one end, of a second slotted plate adjustably secured to said first plate which projects through the down-turned flange of said first plate and is provided adjacent one end with a down-turned edge or second gauge in spaced cooperation with the first mentioned gauge, and an adjustable clamping device adapted to secure the plates together in adjustably spaced relation. 65

ELLA M. BEADLE. 70
